TUBE ROLLER

John J. Begley, Arlington, Mass., assignor to Mutual Boiler Insurance Company, Boston, Mass., a corporation of Massachusetts

Application December 27, 1946, Serial No. 718,763

7 Claims. (Cl. 153—39)

1

This invention relates to a tube roller and more particularly to such a roller which is adapted to return to its normal position in the wall of a tube, a bulge or other irregularity formed thereon.

Watertube boilers comprise a series of metallic tubes the surfaces of which are subjected to heat while water is circulated through the interior thereof. The steam generated in such boilers is utilized for heating, power and processing of various kinds. Bulges frequently form on such a tube due to the formation of localized heat insulating areas on the wall of the passage of the tube and each such area causes localized overheating of the adjacent portion of the wall of the tube resulting in an outwardly extending bulge. Such areas are caused by deposits of magnesium, calcium or other salts or of oil carried by the water. Such bulges are also frequently caused when the heating means is operated so as to direct a flame at a particular area of the exterior wall of the tube.

As soon as such a bulge begins to form a pocket or depression is formed on the inner wall of the tube and deposits of oil, metallic salts or the like are attracted to the depression so that the insulating effect of the deposit gradually increases causing the bulge to increase in size more and more rapidly. If the bulge is permitted to grow sufficiently the tube bursts requiring a shut down for replacement thereof.

To prevent the bursting of boiler tubes it is customary periodically to shut down the boiler to inspect the tubes and to hammer the bulges thereby to reform the wall of the tube to its original uniform tubular contour. Such an operation is unsatisfactory because of the difficulty of access to the bulges for hammering, because the tubes are frequently supported at their ends so that the tube springs away from the hammer requiring many blows to remove a bulge and because it is substantially impossible to thus hammer a bulge without leaving indentations in the surface of the tube. Furthermore the smaller bulges normally are not thus treated because of the difficulty of removing them by hammering. Accordingly relatively frequent and prolonged shutdowns are necessary with resultant loss of use of the boilers.

While this invention is particularly adaptable for use in rolling bulges of water tube boilers it is not limited to such use and it may be utilized to return to its normal position a bulge or any other deformity in the outer wall of any tube.

An object of the present invention is to pro-

2

vide an apparatus for rolling tubes which eliminates the foregoing disadvantages of the hammering method.

A further object is to provide a novel and efficient tube roller.

Further objects are to provide such a roller which is economical in use and to provide one which may be produced economically.

Further objects and advantages will be apparent from a consideration of the following description and the accompanying drawings in which

Fig. 1 is a side elevation of a tube roller embodying this invention;

Fig. 2 is a section on the lines 2—2 of Fig. 1; and

Fig. 3 is an end elevation, with parts broken away and shown in section, of the upper part of the strap portion of the apparatus of Figs. 1 and 2 and showing two adjustment straps in place therein.

The U-shaped rigid strap member, indicated generally by the numeral 10, consists of a pair of legs 11 and 12 and the end portion 13, which is formed to provide a concave inner wall adapted to engage the exterior wall of a tube 14. Perforations 15 are provided adjacent to the ends of the legs 11 and 12.

A mounting member 16 is mounted for pivotal movement between the legs 11 and 12. The ends of this mounting member 16 are provided with ears 17 which are small enough to be passed through the perforations 15 but which are long enough to prevent accidental removal of the mounting member while in use.

The mounting member 16 is provided intermediate its ends with an interiorly threaded transverse passage through which extends the exteriorly threaded portion 19 of the handle 20.

The U-shaped roller support 21 is secured to one end of the handle 20 and supports the roller 22 for rotation about its longitudinal axis. The roller 22 preferably is provided with a concave surface as illustrated.

Thus with the strap 10 in place upon the tube 14 the legs 11 and 12 support the mounting member 16 which in turn supports the handle 20 and roller 22. The distance between the longitudinal axis of the roller 22 and the mounting member 16 may be varied by turning the handle 20 about its longitudinal axis thereby causing longitudinal travel of the handle relative to the mounting member 16 due to the interengagement of the threads 19 with the threads on the wall

55 of said transverse passage. In such position

of the strap the mounting member may also be rotated about its pivotal connections with the legs 11 and 12 by raising or lowering the handle 20; the surfaces of the end portions of the mounting member slide upon the walls of the perforations 15 during such rotation.

To adjust the strap 10 for use with tubes of smaller diameter supplemental straps 25, 26 (Fig. 3) may be provided. The end portion 13 of the strap 10 is provided with a perforation 27 adapted loosely to receive the lug 28 which is provided on the corresponding end portion of the strap 25. The end of the strap 25 is also provided with a cavity adapted loosely to receive the lug 29 which is provided on the end portion of the strap 26. Thus the strap 10 may be supplemented with the strap 25 by merely inserting the lug 28 in the perforation 27 and it may be further supplemented with the strap 26 by inserting the lug 29 in said cavity of the strap 25. Additional supplemental straps may be provided by providing the end portion of the strap 26 with a cavity beneath the lug 29 to receive a projecting lug of a supplemental strap.

Preferably the roller 22 and the strap 10 are made of high grade steel or its equivalent.

In operation the strap 13 is lowered upon the tube 14 adjacent to the bulge 30, so that the concave end portion of the strap rests upon the wall of the tube. One end of the mounting member is then passed through the perforation 15 of one of the legs 11 and by sliding the mounting member from left to right looking at Fig. 2 the opposite end of the mounting member may then be inserted in the perforation 15 of the other leg 12 and the mounting member is then pivotally supported by the legs 11 and 12 as illustrated in Figs. 1 and 2. The distance between the longitudinal axis of the roller 22 and the longitudinal axis of the mounting member 16 is then adjusted by turning the handle 20 about its longitudinal axis. The roller is then caused to traverse the bulge 30, or a portion thereof by moving the handle 20 up and down thus causing rotation of the roller about its longitudinal axis and rotation of the mounting member 16. The bulge may be smoothly and evenly returned to the original tubular contour of the tube, by periodically moving the strap 10 longitudinally of, and axially of, the tube 14 and by periodically increasing the distance between the axis of the roller 22 and the axis of the mounting member 16; it being understood of course that the operator rolls the bulge between each such movement and adjustment by reciprocation of the handle 20.

The apparatus is removed from the tube by moving the mounting member 16 from right to left looking at Fig. 2 while concomitantly slightly elevating the mounting member and thus withdrawing one end of the mounting member from the perforation 15 in the leg 12. That end is then lowered and the mounting member is moved from left to right looking at Fig. 2 thus withdrawing the other end from the perforation in the leg 11. The strap 13 is then withdrawn from the tube 14 the tube passing through the open end of the strap.

Use with one or more supplemental straps 25, 26, is the same except that the straps are first nested in the strap 10 (as shown in Fig. 3) prior to placing the apparatus upon the tube.

From the foregoing it will be apparent that I have provided a novel and efficient tube roller

which is economical in use and in production and which eliminates the disadvantages of the hammering method of the prior art.

It should be understood that the present disclosure is for the purpose of illustration only, and that this invention includes all modifications and equivalents which fall within the scope of the appended claims.

I claim:

1. A tube roller comprising a U-shaped strap member adapted to straddle a tube, said strap member including a pair of legs and an end portion extending between the legs and a roller mechanism having one end pivotally supported by one of said legs and the other end pivotally supported by the other leg thereby to form an axis of pivotal movement for the roller mechanism, said roller mechanism comprising a roller adapted to bear on the tube and mounted for pivotal movement about an axis located in offset relationship to said axis of pivotal movement for the roller mechanism, and means by which in use the roller mechanism is moved about its said axis for pivotal movement.

2. The combination of claim 1 wherein the means by which the roller mechanism is moved about its said axis for pivotal movement comprises a handle operatively connected to the roller mechanism.

3. The combination of claim 1 wherein said roller mechanism comprises a mounting member extending between said legs and having one end pivotally supported by one of said legs and the other end pivotally supported by the other leg, thereby forming said axis of pivotal movement for the roller mechanism, and a roller support mounted on said mounting member, said roller being pivotally mounted on said support.

4. The combination of claim 3 wherein said roller mechanism includes an adjusting mechanism associated with said roller support and said mounting member whereby the distance between the axes for pivotal movement of the roller and of the roller mechanism may be varied.

5. The combination of claim 4 wherein the adjusting mechanism comprises an exteriorly threaded rod secured to the roller support and an interiorly threaded transverse passage through the mounting member, the threads of said rod operatively engaging the threads of said passage whereby the distance between the axes for pivotal movement of the roller and the roller mechanism may be varied by rotation of said rod.

6. The combination of claim 5 wherein the adjusting mechanism comprises a single rod, the roller support comprises a bifurcated member secured to one end of said rod and the roller is pivotally mounted between the bifurcated portions of said bifurcated member.

7. The combination of claim 6 wherein the rod includes an extension forming the means by which the roller mechanism is moved about its axis for pivotal movement in use.

65 JOHN J. BEGLEY.
